INKING APPARATUS FOR PRINTING MACHINES

William Gibson Thomlinson, Glasgow, Scotland

Application September 10, 1946, Serial No. 695,973
In Great Britain September 18, 1945

4 Claims. (Cl. 101—348)

1

This invention relates to printing machines, and in particular to means for regulating the distribution of the ink on the inking rollers.

The object of the invention is to provide simple means of controlling the ink supply whereby to eliminate preliminary adjustment and maintain an approximately even film on the inking rollers which ink the forme, thus saving considerable time in setting-up any particular printing job.

A practical embodiment of the invention is illustrated in the accompanying drawings in which Fig. 1 is a semi-diagrammatic view of a printing machine to which the invention is applied. Fig. 2 is an end elevation of an auxiliary roller, Fig. 3 is a front elevation of the same roller and Fig. 4 is a plan view of the roller, Fig. 5 is a large scale view of the tilting mechanism at one end of a roller, the mechanism at the other end of the roller being similar but of the opposite hand, and Fig. 6 is a fragmentary view at the end of a roller. Fig. 7 is an elevation of the roller traversing gear, and Fig. 8 is a plan view of the same gear. Figs. 9a, 9b, 9c and 9d are diagrams showing the roller in four different positions. Fig. 10 is a semi-diagrammatic cross section of a printing machine through the line A—A in Fig. 1.

In the drawings, 1 denotes a metallic shell forming an auxiliary roller, 2 denotes a ring attached to the metallic shell 1, 3 denotes a boss encircled by the ring 2. The said boss 3 is formed with an oblong slot 4 through which passes a non-rotary polygonal bar 5 fitted in a bracket 6 secured to the frame 7 of the printing machine. 8 denotes main rollers on which the auxiliary rollers 1 are adapted to run freely.

A spindle 9 is journaled in a bracket 10 secured to each slotted boss 3. One end of each spindle 9 carries a crank arm 11 furnished with a roller 12. The other end of the spindle carries an arm 13 pivotally connected to a rod 14 which carries a two-armed pawl 15 pivoted at 15¹ to the rod 14, see Fig. 8, and adapted to engage periodically a reciprocating toothed bar 16 attached to a rod 16² which receives its reciprocating motion from a convenient existing shaft 16¹ on the machine through the linkages shown in Fig. 10, 16³ denotes teeth attached to the bar 16.

A spring bar 17 slidably mounted on the rod 14 and bent to form a projection 18 is adapted to engage the two-armed pawl 15 by the projection 18 when the bar 17 is moved in one direction or the other. Stops 19 and 19² are mounted one at each end of the toothed bar 16 the appropriate one of said stops being each adapted to engage the adjacent end of the spring bar 17 when the

2

auxiliary roller 1 reaches the end of its travel in one direction. 18¹ is a rider running freely on the main rollers 8; 19² are ink distributing rollers fed from an ink fountain shown conventionally at 20; 21 are type inking or "forme" rollers; 22 denotes an ink table adapted to reciprocate lengthwise of the machine, and 23 denotes a cylinder around which the sheet to be printed is wrapped.

10 In operation, assuming that the auxiliary roller 1 has reached one end of its travel widthwise of the machine, the spring bar 17 will have come into engagement with the stop 19 and will have been pushed to the right when viewed as in Fig. 16. The projection 18 on the spring bar 17 in engagement with the two-armed pawl 15 endeavors to move the pawl 15 to the right along with the bar 17, but as the pawl is pivoted on the pin 15¹ located at the same side of the pawl 15 as the bar 17 the effect is to swing the said pawl about the pin 15¹ in counter-clockwise direction when viewed as in Fig. 4. The left-hand arm (Fig. 4) of the pawl 15 will thus be swung into engagement with the toothed bar 16. The auxiliary roller 1 will be in the position shown in Fig. 9a.

In reciprocating, the toothed bar 16 will be moved to the right (see Fig. 4); one of the teeth of the bar 16 will engage the left-hand arm of the pawl 15 and urge it to the right. The pawl 15 will move to the right and will carry with it the rod 14, resulting in the arms 13 pivotally connected to the rod 14 at each end of the roller rotating in clockwise direction when viewed as in Fig. 6. Consequently, the spindles 9 and the crank arms 11 are also caused to rotate in clockwise direction, Fig. 6, resulting in the roller 12 at the left-hand end of the auxiliary roller 1, as seen in the drawings, being lifted clear of the polygonal bar 5, the corresponding roller at the right-hand end of the auxiliary roller 1 being pressed hard against the polygonal bar 5 until the pressure on the roller causes it to act as a fulcrum and to lift the right-hand end of the auxiliary roller 1 away from the main roller 8 on which it was revolving. The oblong slot 4 in the boss 3 permits the end of the roller 1 to rise, the polygonal bar 5 sliding to the bottom of the oblong slot 4 as the roller 1 rises. The auxiliary roller 1 is now in the position shown in Fig. 9b.

50 Continued movement of the bar 16 to the right moves the roller 1 along the main roller 8 until the said roller 1 reaches the position shown in Fig. 9c. The direction of movement of the toothed bar 16 is now reversed and starts travelling to the left when viewed as in Fig. 4. The

tooth on the rack which had been urging the pawl 15 and consequently the bar 14 towards the right now moves to the left in unison with the rack and out of contact with the pawl 15, and the right-hand end of the roller 1, having now nothing to support it, drops gently back into contact with the main roller 8 below and takes up the position shown in Fig. 9d.

Continued movement of the bar 16 to the left brings another tooth past the pawl 15 which trips over this other tooth by flexure of the bar 17, said other tooth being nearer that end of the toothed bar 16 to which the roller 1 is travelling than the first mentioned tooth. When the bar 16 is again moved to the right, the last mentioned tooth on the bar 16 will engage the same end of the pawl 15 which is still urged towards the bar 16 by the spring bar 17 in the same manner as the first mentioned tooth and the cycle will be repeated, the auxiliary roller 1 being moved in tilted position a further distance to the right.

These cycles are repeated until the auxiliary roller 1 reaches the right-hand end of the main roller 8 whereupon a stop 19³ on the right-hand end of the bar 16 engages the right-hand end of the spring bar 17 as viewed in Fig. 4 and pushes it to the left; the projection 18 on the said spring bar 17 in engagement with the two-armed pawl 15 endeavors to move the said pawl to the left along with the bar 17, the effect being to swing the pawl 15 about the pin 15¹ in clockwise direction as viewed in Fig. 4. As the pawl is pivoted on the pin 15¹, the right-hand arm of the pawl 15 is swung into engagement with the bar 16, whereupon the movements above described will be performed in reverse, the roller 1 now moving across the main roller 8 in steps to the left.

For the sake of clarity only one auxiliary roller is shown in the detail figures of the drawings but normally two are used as shown in Fig. 1. The two rollers are set initially at opposite ends of their respective main rollers and travel in opposite directions.

What is claimed is:

1. In a printing machine having at least one main inking roller disposed widthwise of the machine, ink distributing mechanism comprising at least one auxiliary roller adapted to make line contact with said main inking roller, means to tilt said auxiliary roller relatively to the surface of said main inking roller so that only one end of said auxiliary roller remains in contact with said main inking roller, means to move the tilted auxiliary roller in steps widthwise of the machine, and means to reverse the direction of movement of said auxiliary roller when its travel in one direction has been completed.

2. Ink distributing mechanism as claimed in claim 1 in which the auxiliary roller comprises a cylindrical shell having bosses, one at each end

5 of said shell and each formed with an oblong slot, rings, one encircling each boss, a polygonal bar fixed at its ends, said bar passing through the slots in said bosses and disposed parallel to the main inking roller, said shell being free to rotate on said bosses, the slots being of such dimensions as to permit tilting movement of said shell relatively to said bar.

3. Ink distributing mechanism as claimed in claim 1 in which the auxiliary roller comprises a cylindrical shell having slotted bosses, one at each end of the shell, and a bar penetrating the slots in said bosses, and in which the means for tilting the auxiliary roller and moving it in steps widthwise of the machine includes a rod extending and movable widthwise of the machine, rocking spindles each supported by a boss, two arms pivotally attached to said rod, said arms being each fixed at the end remote from the rod to its respective spindle, a crank attached to each spindle at the end of the spindle remote from the respective arm, a fulcrum roller carried by each crank, each fulcrum roller being positioned above and engageable with said bar on movement of said rod in one direction whereby to lift the respective boss and to tilt the auxiliary roller, a pawl pivoted on said rod, and a toothed bar reciprocable widthwise of the machine and periodically engageable by said pawl, whereby reciprocatory movement of the toothed bar is communicated in steps to said rod and thereby to the auxiliary roller.

4. Ink distributing mechanism as claimed in claim 1 in which the means for moving the auxiliary roller in steps widthwise of the machine includes a rod extending and movable widthwise of the machine, a two-armed pawl pivoted on said rod, and a toothed bar reciprocable widthwise of the machine and periodically engageable by said pawl, and the means for reversing the direction of movement of the auxiliary roller includes a spring bar slidably mounted on the rod and having a projection adapted to come into contact with either of the arms of said pawl, and a stop at each end of the toothed bar adapted to engage said spring bar and cause it to be slid widthwise of the machine when the auxiliary roller has come to the end of its travel in one direction.
